UNITED STATES PATENT OFFICE

HERBERT E. KEMPTON AND KEITH F. GALLIMORE, OF FOND DU LAC, WISCONSIN,
ASSIGNORS, BY MESNE ASSIGNMENTS, TO THE HEALD MACHINE COMPANY, OF
WORCESTER, MASSACHUSETTS, A CORPORATION OF MASSACHUSETTS

GRINDING MACHINE

Application filed February 4, 1925. Serial No. 6,689.

This invention relates to improvements in grinding machines, and is herein shown as embodied in an internal grinding machine of the type disclosed in U. S. Letters Patent No. 5 1,534,302, issued April 21, 1925, to Prentice Conradson and ourselves.

A general object of the invention is to provide a grinding machine with a novel automatic wheel truing device the operation of which is incidental to and controlled by the main operation of the machine. 10

The primary object of the invention resides in the provision, in a grinding machine, of 15 automatic means for dressing and truing the grinding wheel before the workpiece is brought to the desired size. According to this feature of the invention, therefore, the wheel truing operation is interposed in the cycle of grinding, so that the final and finishing cuts, which bring the workpiece to the desired size, are taken with a wheel which is not only sharp and clean cutting, but is of truly cylindrical shape. It will be seen that the foregoing has the greatest utility in a 20 grinding machine having automatic means for causing cessation of the grinding operation, for in this manner a high production can be attained while maintaining high precision standards for the finished workpieces. 25

A second important feature of the invention resides in the fact that the dressing operation, which takes place automatically as above mentioned, is effected by withdrawing the grinding wheel from the workpiece, moving the grinding wheel past a dressing device, and subsequently returning the wheel to the workpiece. The workpiece is brought to the finished size, according to this feature of the invention, by a wheel which maintains 30 continuous contact with it, albeit the usual reciprocatory traverse motion between wheel and workpiece is employed. In this manner detrimental bell-mouthing of the workpiece (in the case of an internal grinding machine) 35 or excessive grinding of the end surface of the work (in the case of grinding machines generally) is avoided.

Still another feature of the invention resides in the employment of the carriage moving mechanism to effect the dressing opera-

tion aforesaid. Most grinding machines, including internal grinding machines, are provided with a table or carriage, carrying indifferently the grinding wheel or the workhead, and by the movement of which a reciprocatory traverse between wheel and workpiece is secured. The purpose and utility of this motion is too well known to require discussion here. We utilize this carriage moving mechanism as aforesaid, the novelty residing in the control thereof and in the automatic increased traverse interposed in a succession of limited traverses. 55

A more specific object resides in the provision for grinding machines of a novel wheel truing device which has a dressing tool adapted to be projected into the path of the grinding wheel, and the operation of which is automatically controlled by the progress of the grinding operation. 60

A further object is to provide means for slowing down the movement of the grinding wheel carriage while the cutting face of the grinding wheel is moving past the dressing tool in the truing operation. 70

A detailed object is to provide a high speed grinding machine which has a grinding wheel carriage; which has means to automatically gage the work; which has means controlled by said gaging means for effecting relative coarse and fine cross feeds between said carriages; which has pressure-fluid-operated means under the control of said gaging means for advancing said grinding wheel carriage from its remote inoperative position into its operative position and reciprocating it in the latter position, returning said carriage part way to its inoperative position upon stopping the coarse cross feed, immediately advancing said carriage again 80 into its operative position and reciprocating it therein, and finally returning said carriage to and stopping it in its inoperative position upon stopping the fine cross feed; and which has a wheel truing means also controlled by said gaging means to dress the grinding wheel directly after the coarse cross feed as the grinding wheel carriage is moving toward its inoperative position the first time 85 in the above cycle. 90

A further object is concerned with the electrical devices and circuits by which the various parts of the machine are automatically operated in harmony and synchronism.

5 Ancillary objects and advantages will become apparent as the description proceeds.

In the accompanying drawings, Figure 1 is a front side view of a grinding machine embodying the features of our invention in 10 its preferred form, and of which parts have been broken away to show the gage member.

Figure 2 is a top plan view of the machine.

Fig. 3 is a rear side view of the machine.

Fig. 4 is a diagrammatic representation of 15 the electric circuits and the hydraulic system for operating and controlling the machine parts, certain of the latter being shown in part or in section.

Fig. 5 is a fragmentary view of a modified 20 form of dressing means adapted to be hydraulically operated.

Fig. 6 is a vertical section through the feed mechanism taken along line 6—6 of Fig. 2.

Fig. 6^a is a fragmentary side view of one 25 of the locking means for the electromagnets of the feed mechanism.

Fig. 7 is a sectional view taken along line 7—7 of Fig. 1 and showing the double switch controlled by the gage member.

30 Fig. 8 is a fragmental vertical section through the control means governing the movements of the grinding wheel carriage, said section being taken substantially in the plane of line 8—8 of Fig. 1.

35 Fig. 9 is a sectional view of the reversing switch controlling the movement of the grinding wheel carriage.

Fig. 10 is an enlarged sectional view of the dressing mechanism shown in Fig. 2.

40 Fig. 11 is a perspective view of one of the reversing dogs.

Fig. 12 is a perspective view of another dog.

While our invention is susceptible of various modifications, alternative constructions, and adaptations, we have shown in the drawings and will herein describe in detail the preferred embodiment, but it is to be understood that we do not thereby intend to limit 50 ourselves to the specific form disclosed, but aim in the appended claims to cover all modifications, alternative constructions and adaptations falling within the spirit and scope of the invention.

55 Referring now more particularly to the specific construction of the exemplary embodiment of the invention, the machine comprises a hollow base casting 10 having an internal transverse wall 11 which separates the base 60 into a long bed on which a grinding spindle carriage 12 is mounted and a wide portion on which a headstock carriage 13 is mounted. Between the wall 11 and another transverse wall 14 is a chamber adapted to contain a 65 coolant fluid for the work, and between the

wall 14 and a third transverse wall 15 is a reservoir adapted to contain a pressure fluid, such as oil, for actuating the carriages 12 and 13.

The grinding spindle carriage

70

The grinding spindle carriage 12 is mounted to reciprocate on suitable ways 16 extending longitudinally of the base 10, and is provided with sides 17 overhanging the side walls 75 of the base. Rotatably mounted in the carriage 12 is a spindle 18 which carries a grinding wheel 19, and which is driven by a belt 20 from an electric motor 21 mounted on the underside of the carriage to travel therewith.

80 The carriage 12 is arranged to be reciprocated by a piston and cylinder unit, one element of which is mounted on the carriage to travel therewith. Preferably the cylinder 22 is rigidly secured to the underside of the carriage 12, and the piston 23 is stationarily supported by hollow rods 24 having their remote ends mounted in the machine base. These rods communicate with the cylinder 22 at opposite sides of the piston 23 to introduce and 85 permit the escape of pressure fluid.

The headstock carriage

The headstock carriage 13 comprises a body section 25 which is slidably mounted on transverse ways 26 formed on the base 10, and a top section 27 which is rotatably mounted in the body section and extends therethrough into the base 10. Journalized in the top section 27 is a rotary work spindle 28 which carries a suitable chuck or work fixture 29 at one end for holding the work to be ground, and which is driven through suitable connections including a change speed gearing 30 by an electric motor 31 mounted with the gearing on the underside of the top section to move or rotate therewith.

120

125

130

The feeding mechanism

The headstock carriage 13 is arranged to be fed along the ways 26 to move the work against the grinding wheel 19 by means of a feed screw 32 mounted on the base 10 and engaging in a part of the body section 25 of the carriage. The outer end of the feed screw 32 extends through a feed box 33, and is provided with a hand wheel 34 whereby it may be manually rotated. Within the feed box, a ratchet wheel 35 (see Fig. 6) is fixed on the feed screw, and is adapted to be rotated intermittently and by small degrees by means of either one of two feed pawls 36 and 37. These pawls are pivotally mounted on the oppositely extending arms of two bell-crank levers 38 and 39, respectively, loosely supported by the feed screw 32, and are drawn toward the ratchet wheel 35 by springs 40. The other arms of the bell-crank levers extend in the same direction, and are provided with cams 41 adapted to be engaged by a lever 42 to re-

5 ciprocate the pawls. The degree of oscillation of these arms can be independently adjusted by means of two eccentrics 43 underlying them and limiting the downward movement of the cams 41. In practice, the eccentrics 43 are so adjusted that the pawl 36, designated as the "coarse feed pawl," is given a relatively large reciprocation, and the pawl 37, designated as the "fine feed pawl" is given 10 a relatively small reciprocation. The lever 42 is oscillated by means of a floating piston 44 reciprocable in a stationary cylinder 45, the opposite ends of which alternately receive and discharge pressure fluid.

15 10 Mounted in the feed box 33 are a pair of electromagnets 46 and 47 provided with armatures 48 and 49 having tracks 50 and 51 respectively. The latter underlie rollers 52 and 53 on the pawls 36 and 37, and upon excitation of the electromagnets will render the pawls inoperative. Upon first exciting the electromagnet 46 and then the electromagnet 47, the pawls 36 and 37 will be successively rendered inoperative, thereby reducing and 20 finally discontinuing the cross feed of the headstock carriage 13 as the grinding operation progresses. To permit manual operation of the feed screw by means of the hand wheel 34, the pawls 36 and 37, after each excitation 25 of the electromagnets, are automatically locked in inoperative position by a pair of latches 54 engaging the heels of the armatures 48 and 49. The latches 54 are mounted on a pair of shafts 55 together with releasing levers 56 which are connected by a suitable linkage and which can be oscillated simultaneously by a lever 57 to disengage the latches and thereby release the pawls.

40 The gaging mechanism

Extending slidably and axially through the work spindle 28 and into the chuck 29 is a gage rod 58 having a pair of gages 59 and 60, designated respectively as a "coarse feed 45 gage" and a "fine feed gage", mounted on its forward end. These gages are adapted to gage the work being ground, such as the blank A centrally mounted in the chuck 29, and the gage 59 is slightly smaller and a little in advance of the gage 60 to permit the former to enter the bore of the blank sometime before the latter. The rear end of the gage rod 58 is connected by a bracket 61 to that of a parallel push rod 62 reciprocable in the top section 27 and carrying an abutment roller 63 at its forward end. A coil spring 64 on the push rod 62 tends to move the gages forward into yielding engagement with the blank A, and an adjustable abutment 65 on the grinding spindle carriage 12 is adapted to strike the roller 63 to withdraw the gages as the grinding wheel 19 advances into the bore of the blank. The gages thus automatically and periodically attempt to enter the bore of the work. When the grinding operation nears

completion, the "coarse feed gage" 59 only will enter the bore, and when the operation is completed both gages will enter.

Mounted on the bracket 61 and extending longitudinally into a pair of insulating tubes 66 on the top section 27 of the headstock carriage 13 are a pair of spring pressed contacts 67 and 68 (see Fig. 7) which are movable with the gage rod 58 and which are adapted to successively engage two pairs of contact pins 69 and 70, projecting into the tubes, as the gages 59 and 60 respectively enter the bore of the work.

These contacts and contact pins constitute two switches 71 and 72 (see Fig. 4) respectively, which upon being successively closed, serve to close first the circuit through the electromagnet 46 and then the circuit through the electromagnet 47 to control the progress of the grinding operation in a manner already described.

The operating mechanism

Hydraulic pressure fluid, preferably oil, is drawn from the oil reservoir in the machine base 10 through a pipe 73 (see Fig. 3) by an oil pump 74 driven by an electric motor 75, said pump and said motor being mounted on the rear side of the base. The oil is discharged from the pump 74 through a pipe 76 which communicates with the inlet port 77 (see Figs. 1 and 4) of a main control valve 78 mounted on the front side of the machine. This valve is formed with ports 79 and 80 connected to the remote ends of the hollow piston rods 24 for the grinding spindle carriage 12 by pipes 81 and 82, and to opposite ends of the cylinder 45 for the feeding mechanism by pipes 83 and 84 branching from the first mentioned pipes. Spent oil flowing back to the valve 78 through either of the ports 79 or 80 is returned through the outlet ports 85 to the oil reservoir. The flow of oil through the valve 78 is controlled by a reciprocable valve member 86 adapted to connect the ports 79 and 80 successively and alternately with the ports 77 and 85. When the valve member 86 is in a central or neutral position, the oil will be by-passed directly from the inlet port 77 to the outlet ports 85. The volume of the oil can be changed to vary the speed at which the carriages 12 and 13 move by means of a hand lever 87 for adjusting a change speed gearing 88 in the connection between the motor 75 and the pump 74.

The valve member 86 is provided with a stem 89 pivotally connected to the lower end of an actuator which is in the form of an upright lever 90 pivoted between its ends at 91 on the machine base. Movement of the lever 90 to the right or left will reciprocate the valve member 86 to cause movement of the spindle carriage 12 toward or from the chuck 29 (see Figs. 1 and 8). A pivoted dog 92 is mounted in the upper end of the

lever 90, and is normally maintained by a spring follower 93 in operative position in the path of three dogs 94, 95 and 96 (see Figs. 1 and 4) which are adjustably secured to the front depending side 17 of the carriage 12 by bolts engaging in the T-slot 97. The dogs 95 and 96 are beveled at their left ends, and upon movement of the carriage 12 from its inoperative position, shown in Fig. 1, to the left will successively engage and depress the pivoted dog 92 out of their way to permit the latter to snap into position between the dogs 94 and 95. Upon continued movement of the carriage 12, the dogs 94 and 95 will automatically oscillate the lever 90 to reciprocate the carriage. The distance through which the carriage will reciprocate depends upon the spacing of the dogs 94 and 95, and corresponds to the length of the bore 20 in the piece of work to be ground, the dogs being so positioned on the carriage that the grinding wheel 19 will reciprocate from one end of the bore to the other.

Means is provided for automatically tripping the pivotal dog 92 when the coarse feed gage 59 and also when the fine feed gage 60 enters the work. This means comprises an electromagnet 98 (see Figs. 8 and 4) mounted in a suitable housing 99 secured to the base of the machine, and having a pivotal armature 100 to the free end of which a slidable pin 101 is attached. The pin 101 is arranged to engage the dog 92 and swing it out of the path of the dogs 95 and 96, but not far enough to be out of the path of the dog 94. A catch 102 mounted in the housing 99 is adapted to drop behind the pin 101 when the armature 100 is attracted by the magnet coil to hold the dog 92 in tripped position. The catch 40 102 is provided with a pin or projection 103 which is adapted to ride upon a cam face 104 on the dog 95 and also upon two cam faces 105 on opposite sides of a dog 106 mounted on the left end of the carriage 12, and which is 45 thereby adapted to release the pivotal dog 92 if the electromagnet 98 is deenergized.

Excitation of the electromagnet is controlled by a suitable switch mechanism which comprises a casing 107 mounted on the front 50 of the machine base (see Figs. 1 and 9). Mounted on insulating sleeves 108 in opposite ends of the casing 107 are three fixed contacts 109 and two fixed contacts 110 respectively. Two movable contacts 111 and 55 112 are slidably mounted on the reduced opposite ends of a reversing piston or plunger 113 reciprocable in the casing 107, and are adapted to selectively close the contacts 109 and 110 with which they constitute switches 60 114 and 115 respectively (see Fig. 4). A pair of coil springs 116 on the plunger 113 tend to press the contacts 111 and 112 outwardly against a pair of heads 117 on the extreme ends of said plunger.

65 The plunger 113 engages and is adapted

to be reciprocated by the downwardly extending arm of a switch lever 118 pivotally mounted at 119 to the front of the machine base. Formed on the lower end of the lever 118 is a wedge shaped projection 120 which engages either side of a pointed spring detent 121 mounted in the casing 107 to hold the plunger 113 resiliently in one extreme position or the other. The lever 118 is formed with an inclined arm which extends over the control lever 90, and which supports a cam roller 122 at its extreme end in the path of the dogs 95 and 106.

In the final movement of the carriage 12 to inoperative position, the cam roller 122 will ride onto a cam face 123 on the dog 106 and thereby move the plunger 113 to the right to close the switch 114. Upon a subsequent closure of the switch 71 by entry of the coarse feed gage 59 into the bore of the work, circuits through the electromagnets 46 and 98 respectively will be completed as follows: from the plus main, through wire 124, the switch 71, and wire 125 to the switch 114, thence branching through wire 126, the electromagnet 98, and wire 127 to the minus main, and through wire 128, the electromagnet 46, and wire 129 to the minus main. In the return movement of the carriage to operative position, the cam roller 122 will engage an upper inclined cam face 130 on top of the dog 95, which will raise the roller out of its normal position and thereby move the plunger 113 still further to the right relatively to the contacts 109 and against the force of the adjacent spring 116. After passing over the dog 95, the roller under the influence of the spring 116 will snap back into operative position, and the switch 114 will still be closed.

Upon the termination of the coarse cross feed of the carriage 13 and the simultaneous excitation of the electromagnet 98, the pivoted dog 92 will be tripped, thereby rendering the dog 95 ineffectual to oscillate the lever 90, and permitting the carriage to travel toward its inoperative position and withdraw the grinding wheel from the bore of the work. In this movement, directly after the pivotal dog 92 is positioned to the left of the right edge of the reversing dog 95, a sharp cam face 131 on the latter engages and depresses the cam roller 122, thereby opening the switch 114 and closing the switch 115. This results in deenergizing the electromagnet 98, and, since the cam face 104 will raise the catch 102, in the release of the pivotal dog 92 to operative position between the dogs 95 and 96. The dog 92 will subsequently be engaged by the dog 96 to oscillate the lever 90 and reverse the travel of the carriage 12, and will then slide along the cam face 132 again into operative position between the reversing dogs 94 and 95. The roller 122 will pass under the cam 131 on the

70

75

80

85

90

95

100

105

110

115

120

125

130

dog 95, and will therefore be unaffected. The distance that the grinding wheel is temporarily removed from the work is determined by the position of the dog 96.

5 Closure of the switch 115, and subsequent closure of the switch 72 by entry of the fine feed gage 60 into the bore of the work serve to complete circuits through the electromagnets 47 and 98 as follows: from the plus main, through the wire 124, the switch 72, and wire 133, then branching through the electromagnet 47 and the wire 129 to the minus main, and through the switch 115, the wire 126, the electromagnet 98, the wire 127 to the minus main. Thereupon the fine cross feed is discontinued, and the pivotal dog 92 is again tripped to permit movement of the carriage 12 to inoperative position. This time the dog 92 will be held in deflected position irrespective 10 of the position of the catch 102 to permit the carriage 12 to move to its remote inoperative position. In this movement, the cam face 123 of the cam 106 raises the roller 122 to open the switch 115 and close the switch 114.

25 *The dressing mechanism*

The dressing mechanism comprises a housing 135 which is mounted on the front end of a rod 136 slidably and rotatably adjustable in a clamp sleeve 137. The latter is supported by a horizontal rod 138 which is slidably and rotatably adjustable in a clamp sleeve bracket 139 secured to the rear side of the base section 25 of the headstock carriage 13. The housing 135 is formed with a bore 140 in the front end of which a bushing 141 is secured and in the rear end of which a sleeve 142 is slidably mounted. Extending slidably through the bushing 141 and into the front end of the sleeve 142 is a tool holder 143 supporting a cutting tool 144 at its front end. The rear end of the sleeve 142, which is reduced in size, extends through the rear wall of the housing 135, and is provided with an adjusting screw 145 and lock nut 146 for adjusting the relative longitudinal position of the tool holder 143. A bolt 147 which extends through an elongated slot 148 in the housing 135 into threaded engagement with the sleeve 142, and which engages a longitudinal notch 149 in the tool holder 143 serves to hold the parts against relative rotation. The cutting tool 144 when inoperative is located adjacent the path of the grinding wheel 19, and is resiliently held in this position by a coil spring 150 mounted between the bushing 141 and the sleeve 142.

60 Means is provided for projecting the cutting tool 144 into the path of the grinding wheel 19 to automatically dress the peripheral cutting surface of the latter as it is temporarily withdrawn and returned to the work upon completion of the coarse cross feed. This means comprises an electromagnet 151 mounted within the housing 135, and a mov-

able core 152 extending into the rear end of the electromagnet and rigidly connected to the sleeve 142 by a transverse arm 153. It will be evident that upon excitation of the electromagnet 151 the cutting tool 144 will be moved into operative position to dress the grinding wheel 19 as the latter passes by. If at the beginning of the machine operation, the cutting tool 144 were rigidly mounted in line with the edge of the bore of the work blank, it could without being projected forward automatically dress the grinding wheel 19 upon withdrawal of the latter toward inoperative position to a depth corresponding to the depth of the cut on the work. In such arrangement, however, dressing would take place whenever the grinding wheel 19 would be withdrawn from the work past the cutting tool 144. By maintaining the cutting tool 144 in an inoperative position during the actual 70 grinding, and projecting it forward at a predetermined time, any desired depth of dressing cut can be obtained, and dressing can be confined to any desired stage of the grinding operation. Excitation of the electromagnet 151 is controlled by a switch 154 (see Fig. 3) 75 comprising a pair of fixed contacts 155 and a movable contact 156. The fixed contacts are mounted on insulating bushings 157 which extend through the lower wall of a housing 158 secured to the rear side of the machine base 10, and the movable contact 156 is mounted on the lower end of a stem 159 extending slidably through a lug 160 on the inside of the housing. The switch 154 is normally held open by a coil spring 161 mounted on the stem 159 between a head 162 on its upper end and the lug 160. Closure of the switch 154 completes a circuit through the electromagnet 151 as follows: from the plus main, through the wire 124, wire 163, the electromagnet 151, wire 164, the switch 154, wire 165 and wire 129 to the minus main.

Rigidly mounted in the housing 158 is an electromagnet 166 which is adapted to be excited simultaneously with the coarse feed electromagnet 46 and the electromagnet 98. Upon closure of the switches 71 and 114, a circuit through the electromagnet 166 is completed as follows: from the plus main through the wire 124, the switch 71, the wire 125, the switch 114, the wire 128, the electromagnet 166, wire 165, and the wire 129 to the minus main. This circuit is broken when the roller 122 is depressed by the dog 95, and is not again completed upon closure of the switch 72. The electromagnet 166 is provided with a pivotal armature 167 having a latch 168 pivotally secured to its free end. The latch 168 continually overlies and engages the head 162 of the stem 159, and is formed with a hole 169 normally underlying a vertical pin 170 when the armature 167 is in open position. The pin 170 is reciprocably mounted in a tubular projection 171 on the housing 158, and is resiliently 80 85 90 95 100 105 110 115 120 125 130

held above the latch by a coil spring 172. A cam 173 is adjustably mounted on the rear overhanging side 17 of the spindle carriage 12, and is adapted to depress the pin 170 when the grinding wheel 19 is withdrawn from the work. If the electromagnet 166 is excited, the pin 170 will engage the latch 168 to close the switch 154, and thereby actuate the cutting tool 144, but if the armature is in open position, the pin will merely enter the hole 169. 10 Slidably mounted in the projection 171 and pressed downwardly by a coil spring 174 is a catch 175 (see Fig. 5) which upon excitation of the electromagnet 166 is adapted to lock the armature 167 in closed position, and hold it in such position after said electromagnet is deenergized. A second cam 176 formed integral with the right end of the cam 173 and positioned below the same is adapted 15 to engage a lug 177 on the upper end of the catch 175 to raise the latter and release the armature 167. In movement toward the right this release will be ineffectual since the armature 167 will be mechanically held in closed position by pressure from the cam 173 through the pin 170 against the latch 168. In movement toward the left, however, the action of the cam 173 precedes that of the cam 176, and permits the return of the cutting tool 144 to inoperative position while the 20 latter releases the armature 167 to position the hole 169 directly beneath the pin 170.

A modified form of the dressing mechanism is illustrated in Fig. 5, and comprises an elongated pressure fluid cylinder 178 adjustably clamped in the sleeve 137. The cylinder is provided with spaced ports 179 and 180 which are respectively connected by flexible tubes 181 with ports 182 and 183 in a valve casing 184 formed in the housing 158. Extending 25 slidably through the ends of the cylinder 178 is a piston rod 185 which supports the cutting tool 144 at its front end, and a piston 186 midway of its ends. Rearward movement of the rod 185 is limited by a collar 187 thereon adapted to engage the rear end of the cylinder 178, and forward movement is limited by two adjustable lock nuts 188 threaded onto the rear end of the rod. The piston 186 throughout its reciprocation is always positioned 30 between the ports 179 and 180. The valve casing 184 is formed with an inlet port 189 connected by a pipe 190 into the pipe 76 leading to the main control valve 78, and with an exhaust port 191 communicating through a pipe 191^a with the oil reservoir in the base 10. A reciprocable valve member 192 is mounted on the lower end of the stem 159 in the casing 158, and serves to control the flow of oil to 35 and from the cylinder 178. When the stem 159 is depressed in a manner already described, oil will be directed through the port 180 to the rear of the piston 186 and will move the cutting tool 144 into operative position, and when the stem 159 is raised, oil will be

admitted to the front end of the cylinder 178 to return the cutting tool to inoperative position.

Means is provided for automatically reducing the speed of the spindle carriage 12 as the grinding wheel 19 moves past the cutting tool 144 to permit efficient dressing. Preferably this means takes the form of a by-pass valve comprising a valve casing 193 secured to the rear side of the machine base 10. The casing is formed with an oil chamber 194 connected in the pipe 76 leading from the pump 74 to the main control valve 78, and with an exhaust port 195 opening into a pipe 196 leading to the oil reservoir. The port 195 is normally closed by a valve member 197 mounted on the lower end of a valve stem 198, the upper end of which extends slidably through a vertical extension 199 on the casing. The valve member 197 is resiliently held in closed position by a coil spring 200 which engages a collar 201 on the stem 198 and is confined in a bore 202 in the projection 199 by an annular plug 203 encircling the stem. A cam 204 adjustably mounted on the carriage 12 is adapted to depress the stem 198 to by-pass part of the oil in pipe 76 directly to the oil reservoir, thereby slowing down the speed of the carriage. The cam 204 is so positioned that in movement to the right it will engage the stem 198 just before the cam 173 engages the pin 170.

Brief résumé of operation

Assuming the carriage 12 is in its remote inoperative position, shown in Fig. 1, the operation is as follows: A work blank A is centered in the chuck 29, thereby opening the gage switches 71 and 72, and the lever 90 is moved to the right. Thereupon the carriage 12 immediately begins to move forwardly toward the headstock, in the course of which travel the left cam surface 105 raises the catch 102 to release the dog 92 if perchance the electromagnet 98 was excited, the dog 96 deflects and slips over the pivotal dog 92, the dog 95 also deflects and slips over pivotal dog 92, and the dog 94 reverses the lever 90 as the grinding wheel 19 reaches the inner end of the bore in the blank A, in the order named. After feeding the headstock carriage 13 manually to bring the work into engagement with the grinding wheel 19, the handle 57 is actuated to institute the automatic cross feed. Meanwhile the dogs 94 and 95 regularly oscillate the lever 90 to reciprocate the grinding wheel 19 through the work. Upon each reciprocation of the spindle carriage 12, the gages 59 and 60 are withdrawn and advanced toward the work to attempt an entry into the bore.

When the grinding operation has proceeded to the predetermined point at which the coarse feed gage 59 enters the bore of the work the switch 71 closes, and through the

switch 114, which was closed through the agency of the cam face 123 as the carriage 12 moved to inoperative position at the conclusion of the previous operation, completes circuits simultaneously through the electromagnets 46, 98 and 166. The first electromagnet renders the coarse feed pawl 36 ineffectual, the second trips the pivotal dog 92, and the third draws the latch 168 beneath the pin 170. The armature of each electromagnet is automatically locked.

In the movement of the spindle carriage 12 to the right, the dog 95 fails to oscillate the lever 90 to reverse the travel, thereby permitting withdrawal of the grinding wheel 19 from the work. The cam faces 131 and 104 respectively engage the roller 122 thereby breaking the switch 114 to deenergize the three electromagnets and closing the switch 115, and raise the pin 103 to release the pivotal dog 92 into operative position between the dogs 95 and 96. The cam 204 now depresses the stem 198, thereby opening the bypass valve to slow down the speed of the carriage. Immediately thereafter, the cam 173 depresses the pin 170 thereby closing the switch 154, and consequently exciting the electromagnet 151. The cutting tool 144 is thereby projected into the path of the grinding wheel 19, and dresses the latter as it passes by. When the grinding wheel 19 has moved past the cutting tool, the dog 96 oscillates the lever 90 to reverse the travel of the carriage. Thereupon, the grinding wheel 19 repasses the cutting tool 144, the cam 173 releases the pin 170, thereby returning the cutting tool 144 to inoperative position, the cam 176 releases the armature, the cam 204 releases the stem 198, and the dog 92 snaps into position between the dogs 94 and 95 as the grinding wheel 19 re-enters the bore of the work and reciprocates therein.

The grinding operation now continues with only the fine cross feed pawl 37 operative, and when it is completed, the fine feed gage 60 enters the bore of the work, thereby closing the switch 72. This results in the excitation of the electromagnet 47 to discontinue the cross feed, and of the electromagnet 98 to again trip the pivotal dog 92. The latter now permits movement of the carriage 12 to its inoperative position. In this movement the cam face 123 engages and raises the roller 122 thereby opening the switch 115 and closing the switch 114 to place the system in condition for the next operation. The cam face 105 on the right side of the dog 106 raises the pin 103 but does not thereby release the pivotal dog 92 since both switches 71 and 72 are closed. Finally the dog 106 engages the arm 134 to automatically stop the carriage 12 in its inoperative position. Upon reloading the chuck, the gage points 59 and 60 will be forced rearwardly to open the switches 71 and 72, thereby de-

energizing the electromagnet 98. In movement of the carriage 12 to the left to its operative position, the catch 102 will again be raised by the dog 106, and will release the pivotal dog 92.

While in the present operation, the cutting tool dresses the grinding wheel 19 between the coarse and fine feeds, it is to be understood that it can be made to dress the same during any part of the entire operation and without a change of feed thereafter. The machine serves to dress the grinding wheel at the most advantageous time, namely, just before the finishing cuts of the grinding operation. The means is entirely automatic, and efficient and simple in operation.

We claim as our invention:

1. A grinding machine having, in combination, a rotary work holder, a grinding element, means for effecting relative movement between the two to bring the grinding element into and out of operative grinding position with reference to the work, gage means mounted to automatically gage the work during the grinding operation, means controlled by said gage means automatically operable to cause said first mentioned means to remove said grinding element from said work before the completion of the grinding operation, and means operable upon such separation to cause said first mentioned means to return said element to the work to complete said grinding operation.

2. A grinding machine having, in combination, a carriage having a rotary workholder, a carriage having a grinding element, means for driving said carriages relative to each other to reciprocate said element in engagement with the work, means for causing said first mentioned means to automatically discontinue said reciprocation and separate said element from the work, and means automatically operable upon said separation to cause said first mentioned means to return said element to the work to continue the grinding operation.

3. An internal grinding machine having, in combination, a carriage having a workholder, a carriage having a grinding wheel, means for driving said carriages relative to each other, control means for said driving means automatically operable to cause reciprocation between said work and said wheel when in operative relation and to cause a prolongation of said reciprocation in one direction at a point in the operation determined by the progress of said operation and before its completion, and means on one of said carriages automatically operable through said separation to effect through said driving means an immediate return of the work and said wheel into operative relation.

4. A grinding machine having, in combination, a rotary workholder, a grinding element, means for effecting a relative recipro-

cation between the two while they are in continuous engagement, means automatically operable at a predetermined time before the completion of the grinding operation to prolong one stroke of said reciprocation in one direction to effect a temporary separation between said workholder and said element.

5. An internal grinding machine having, in combination, a rotary workholder, a grinding element, mechanism for reciprocating the workholder and said grinding element, one relative to the other while said element is in the bore of the work, and automatic means operable when the work has been ground to a predetermined size to temporarily prolong one stroke of the reciprocating movement in one direction so as to temporarily position said element outside the bore of the work and beyond the range of working reciprocation of said element and said workholder, and to immediately return said element to the bore of the work to continue said reciprocation.

6. A grinding machine having, in combination, a rotary spindle provided with a workholder, a grinding element, means for effecting a relative reciprocation between said holder and said grinding element, a gage mounted to periodically engage the work, means controlled by said gage for effecting a relative cross feed between said holder and said element, and means controlled by said gage for temporarily suspending said reciprocation and causing said first mentioned means to effect a withdrawal from and immediate return to the work of said grinding element.

7. A grinding machine having, in combination, a carriage provided with a work-holder, a carriage provided with a grinding wheel having an operative position relative to the work, means for effecting a relative movement into and out of said operative position and relative reciprocation while in said operative position between said holder and said grinding wheel to grind the work, means for causing said first mentioned means to effect a temporary separation of said grinding wheel and the work to bring said grinding wheel beyond the range of reciprocation before the completion of the grinding operation, a dressing mechanism having a cutting tool, and means controlled by said last mentioned means operable upon said separation to project said tool into a position to be engaged by said grinding wheel.

8. A grinding machine having, in combination, a headstock carriage provided with a work holder, a grinding spindle carriage having a remote inoperative position and an operative position and provided with a grinding element, means for effecting a relative cross feed between said carriages, means for moving said grinding spindle carriage from its remote inoperative position to its operative position, and reciprocating it therein, and means controlled by the progress of said cross

feed to cause said last mentioned means to effect a temporary separation of said grinding element and the work during the grinding operation and to effect a return of said grinding spindle carriage into inoperative position at the completion of the grinding operation.

9. In a grinding machine having a headstock carriage provided with a workholder, a grinding spindle carriage provided with a grinding element and having a remote inoperative position and an operative position relative to said workholder, means for reciprocating said grinding spindle carriage in said operative position, and means for effecting a temporary prolongation of said reciprocation in one direction to separate said workholder and said grinding element at a predetermined point in the grinding operation, a dressing mechanism having in combination, a dressing tool movably mounted at one side of said workholder, and means for projecting said tool into the path of said grinding element in position to dress the cutting surface of the latter at said separation, said last mentioned means being controlled by said second mentioned means to act substantially simultaneously with the initiation of said prolongation.

10. In a grinding machine, a grinding wheel having a reciprocatory working traverse relative to the work, means for automatically procuring an amplified traverse of said wheel when the work, by grinding, has reached a predetermined size, means for automatically disposing a wheel dressing device in the amplified path of movement of said wheel, and means for automatically returning said wheel to its normal working traverse on the return stroke of said amplified traverse.

11. In a grinding machine, a grinding wheel, means operable in the grinding of each work-piece for automatically procuring two successive withdrawals of said wheel from said work, and automatic means for subjecting said wheel to a dressing and truing operation on the first withdrawal, and for avoiding the dressing of said wheel on the second withdrawal.

12. In a grinding machine, a grinding wheel, means operable in the grinding of each workpiece by said wheel for automatically procuring two successive withdrawals of said wheel from the work, each withdrawal carrying said wheel through a wheel dressing position, a wheel dressing device automatically made operable on said wheel during said first withdrawal, and means for automatically preventing the operation of said device on the second withdrawal.

13. In a grinding machine, a grinding wheel, means operable in the grinding of each workpiece by said wheel for automatically procuring two successive passages of said wheel through a wheel dressing position, a

- grinding wheel dresser, means for disposing said dresser in operative position on said first passage and means for maintaining said dresser in inoperative position on said second passage.
14. In a grinding machine, a grinding wheel, a wheel dressing device, a work caliper device, the latter adapted to make a contact at an intermediate stage in the grinding operation to complete an electrical circuit, means dependent upon and set in operation by the completion of said circuit for automatically subjecting said grinding wheel to the action of said dressing device, and means, then acting to break said electrical circuit, thereby to avoid a second dressing operation on said wheel during grinding of the same workpiece, notwithstanding maintenance of the contact made by said caliper device.
15. In a grinding machine, a grinding wheel, a wheel dressing device, means operable automatically at an intermediate stage in the grinding of each workpiece to complete an electrical circuit by making a contact, means dependent upon and set in operation by the completion of said circuit for automatically subjecting said grinding wheel to the action of said dressing device, and means, automatically then acting to break said circuit independently of the contact that completed the same, thereby to avoid a second dressing operation on said wheel during grinding of the same workpiece through the maintenance of said contact.
16. In a grinding machine, a grinding wheel, a wheel dressing device, an electromagnet adapted, when energized, to effect movement of said device into dressing position, a second electromagnet adapted, when energized, to effect movement of said grinding wheel through said dressing position, and means, responsive to the energization of one of said electromagnets, for completing an electrical circuit through the other of said electromagnets.
17. In a grinding machine, the combination with a grinding wheel, of means for causing a relative reciprocatory grinding motion between said wheel and the work, including means for causing a final cessation of said grinding by separation of work and wheel, a dressing tool disposed normally in inoperative relation to said wheel, a work caliper mechanism, means operable by said caliper mechanism, before and in advance of said final cessation of the grinding, for moving said dressing tool into operative position with respect to said wheel, so as to dress the grinding surface of the latter, and means for thereco after disposing said dressing tool in its inoperative position, thereby avoiding engagement of the same with said wheel, upon the separation of wheel and work at the cessation of grinding.
18. In an internal grinder abrading means, work holding means, means operable to separate the work holding means from the abrading means, a feeling finger engaging the inner surface of the work for causing operation of the separating means when the work is finished to separate, and return the work holding means and the abrading means to operative relation, substantially as set forth.
19. In a grinding machine, means for normally effecting relative reciprocation between the grinder and the work without separation of one from the other, means for automatically effecting separation between grinder and work, a dressing device applicable to dress said grinder during said separation, and means for automatically restoring the unseparated normal relative reciprocation between grinder and work.
20. In a grinding machine, means for normally effecting relative reciprocation between the grinding wheel and the work without separation of one from the other, a work caliper device, a grinding wheel dressing device, means responsive to said caliper device for automatically effecting separation between the grinding wheel and the work to subject said grinding wheel to the action of said dressing device, and means for automatically restoring the unseparated normal relative reciprocation.
21. In a grinding machine, a grinding wheel, a work caliper device, means for procuring a relative reciprocatory working traverse between said wheel and the work, a grinding wheel dressing device inoperative on said wheel during said working traverse, means set in operation by said work caliper device for automatically rendering said dressing device operative on said wheel, and means for automatically effecting resumption of said relative working traverse, after the dressing operation.
22. In a grinding machine, a grinding wheel, means for effecting a relative working traverse between said grinding wheel and a workpiece, means automatically operable to separate said grinding wheel and said workpiece, means for automatically subjecting said grinding wheel to a dressing operation during said separation, and means for automatically effecting a resumption of said relative working traverse after said dressing operation.
23. In a grinding machine, a grinding wheel, a wheel dressing device, a work caliper device, means set in operation by said caliper device for procuring an interruption of the grinding operation, and for subjecting said wheel to said dressing device during said interruption, and for automatically procuring resumption of the grinding operation on a workpiece after said dressing operation.
24. A grinding machine having, in combination, a rotary work holder, a grinding ele-

- ment having an operative position in which it is adapted to grind the work, means for effecting a relative movement between the two to bring the grinding element into and out of operative relation with the work, gage means mounted to automatically gage the work, a dressing mechanism having a cutting tool, and means controlled by said gage for controlling said first mentioned means to withdraw said grinding element out of operative relation to the work, it then moving relative to the cutting tool of said dressing mechanism, and said means then returning it to operative position relative to the work.
25. In a grinding machine, a grinding wheel having a reciprocatory working traverse relative to the work, a work caliper device, a wheel dressing device, means set in operation by said caliper device when the work reaches a predetermined size for automatically increasing the traverse of said wheel, thereby to subject it to the action of said dressing device, and means responsive to said increased traverse for limiting the latter to a single reciprocation of said wheel.
30. In a grinding machine, a grinding wheel having a reciprocatory working traverse relative to the work, a grinding wheel dresser, a work caliper device, means set in operation by said work caliper device for increasing the traverse between said wheel and the work in one direction, thereby to subject said wheel to the action of said dresser, and means, responsive to said increased traverse, for automatically restoring the normal working traverse between said wheel and the work.
35. In a grinding machine, a grinding wheel having a reciprocatory working traverse relative to the work, means operable at an intermediate point in the grinding of each workpiece for amplifying said traverse to carry said wheel through a wheel dressing position, a grinding wheel dresser for operating on said wheel in its passage through said dressing position, and automatic means for avoiding the dressing of said wheel by said dresser on the subsequent passage of said wheel through the dressing position at the conclusion of the grinding of the same workpiece.
40. In a grinding machine, means for effecting a relative working traverse between the grinding wheel and the work, means operable automatically before the completion of the grinding operations, to amplify said traverse, a dressing device applicable to dress the said wheel at this stage, and means for automatically resuming said working traverse after said dressing for the final and finishing cuts of the grinding wheel to bring said work to size.
45. In a grinding machine, a grinding wheel, a work caliper device, means for procuring a relative reciprocatory working
- traverse between said wheel and the work, a wheel dressing device disposed beyond the path of said relative reciprocatory working traverse, means set in operation by said work caliper device in advance of the final and finishing cuts taken on each piece of work by said wheel, for automatically amplifying said traverse, thereby to include said dressing device in the path of said wheel, and means for automatically resuming said working traverse, for the final and finishing cuts of the grinding wheel to bring said work to size.
50. In a grinding machine, a grinding wheel having a reciprocatory working traverse relative to the work, means for automatically procuring an amplified traverse of said wheel when the work, by grinding, has reached a predetermined size, means for automatically disposing a wheel dressing device in the path of said wheel on said amplified traverse thereof, and means for automatically resuming the normal reciprocatory working traverse between grinding wheel and work to bring the latter to the desired finished size.
55. A grinding machine having means for effecting a relative working traverse between its grinding wheel and a workpiece, said traverse being substantially coextensive in length with said workpiece, a wheel dressing device beyond the range of said normal working traverse, means automatically operable at an intermediate stage in the grinding operation on each workpiece for separating said grinding wheel and said workpiece, to subject said wheel to the action of said dressing device, and means for automatically restoring said normal working traverse between wheel and workpiece for the final and finishing cuts required to bring each workpiece to the desired size.
60. The combination with a grinding instrumentality, and means for causing a relative motion between it and the work, including means for causing a final cessation of said motion, and a dressing tool, of work engaging caliper mechanism, the position of which changes as the work is ground away, and mechanism operated by such change of position before and in advance of the said final cessation of the grinding motion, for causing an engagement between said dressing tool and grinding instrumentality such as to dress the grinding surface of the latter and then to automatically separate said dressing tool and grinding instrumentality.
65. In a grinding machine, a grinding wheel, a work caliper device, a wheel dressing device, and means successively set in operation by said caliper device, in the grinding of each workpiece, for effecting two separations between the grinding wheel and the workpiece, the first subjecting said wheel to said dressing device, and the second procuring cessation of the grinding operation.

34. In a grinding machine, a grinding wheel, a wheel dressing device, and means responsive to the progressive change in size of each workpiece, during the grinding by said wheel, for effecting successive separations of said wheel from the workpiece, in one instance subjecting said wheel to said dressing device before the work comes to size, and in another instance procuring cessation of the grinding operation when the work comes to size.

35. A grinding machine comprising, in combination, a grinder, a support, a work holder and a truing tool mounted on said support, means for causing relative traverse between the grinder and said support, including means permitting altering the extent of said traverse between two ranges, one of which carries the parts through operative traverse between the grinder and work holder alone, and the other of which carries the parts through operative traverse between the grinder and both the work holder and truing tool, a work sizing mechanism, means brought into action when said work sizing mechanism assumes a predetermined position for altering the said traverse from the shorter to the longer range, means automatically causing resumption of said shorter range, and means preventing immediate subsequent resumption of the longer range despite the assumption by said sizing mechanism of said predetermined position.

36. A grinding machine having, in combination, a support having a rotary work holder, a support having a grinding element means for moving said supports relative to each other to reciprocate said element in engagement with the work, means for causing said first mentioned means to automatically discontinue said reciprocation and separate said element from the work, and means automatically operable upon said separation to cause said first mentioned means to return said element to the work to continue the grinding operation.

37. A grinding machine having, in combination, a headstock provided with a work holder, a grinding spindle carriage having a remote inoperative position and an operative position and provided with a grinding element, means for effecting a relative cross feed between said carriage and said headstock, means for moving said carriage from its remote inoperative position to its operative position, and reciprocating it therein, and means controlled by the progress of said cross feed to cause said last mentioned means to effect a temporary separation of said grinding element and the work during the grinding operation and to effect a return of said carriage into inoperative position at the completion of the grinding operation.

38. A grinding machine having, in combination, a work holder, a grinding wheel, a

carriage supporting and carrying one of said parts, means for moving said carriage to effect a relative movement of said grinding wheel into and out of operative position relative to the work and for effecting a relative reciprocation of said grinding wheel and said work while they are in operative relation in order to grind the work, means for causing said first mentioned means to effect a temporary separation of said grinding wheel and the work to bring said grinding wheel beyond the range of reciprocation before the completion of the grinding operation, a dressing mechanism having a cutting tool, and means controlled by said last mentioned means operable upon said separation to project said tool into a position to be engaged by said grinding wheel.

39. In a grinding machine having a headstock provided with a work holder, a grinding spindle carriage provided with a grinding element and having a remote inoperative position and an operative position relative to said work holder, means for reciprocating said carriage in said operative position, and means for effecting a temporary prolongation of said reciprocation in one direction to separate said work holder and said grinding element at a predetermined point in the grinding operation, a dressing mechanism having in combination, a dressing tool movably mounted at one side of said work holder and means for projecting said tool into the path of said grinding element in position to dress the cutting surface of the latter at said separation, said last mentioned means being controlled by said second mentioned means to act substantially simultaneously with the initiation of said prolongation.

40. An internal grinding machine having, in combination, a support having a work holder, a support having a grinding wheel, means for driving said supports relative to each other, control means for said driving means automatically operable to cause reciprocation between said work and said wheel when in operative relation and to cause a prolongation of said reciprocation in one direction at a point in the operation determined by the progress of said operation, and before its completion, and means on one of said supports automatically operable through said separation to effect through said driving means an immediate return of the work and said wheel into operative relation.

41. In a grinding machine, means for causing relative reciprocation between work holding means and a grinding wheel, a wheel dressing device, means for projecting the wheel dressing device up to the line of the said reciprocation, simultaneously operated means for causing the said reciprocation to include the wheel dressing device in its path, and a control adapted to cause the speed of reciprocation when said dressing device is in

cluded to be different from the speed of reciprocation when said dressing device is not in the said path.

42. In a grinding machine, the combination with a table, means to reciprocate said table, a dressing tool, and means to move said dressing tool into an operative position, of means actuated simultaneously with the movement of said dressing tool into operative position to control said means to reciprocate the table whereby to reciprocate it at reduced speed.

43. A grinding machine comprising in combination a grinder, a support, a work holder and a truing tool mounted on said support, means for causing relative traverse between the grinder and said support including means permitting altering the extent of said traverse between two ranges, one of which carries the parts through operative traverse between the grinder and work holder alone and the other of which carries the parts through operative traverse between the grinder and both the work holder and truing tool, means permitting varying the speed of said traverse, and a device operable to make both of said two last mentioned means effective simultaneously.

44. In a grinding machine, means for causing relative traverse between the grinder and work while the grinder is operating on the work, means for extending the traverse to include the wheel dressing point in the path of reciprocation so that the wheel may be dressed, including means for causing resumption of the aforesaid relative traverse between the grinder and the work, and a control adapted to cause the speed of reciprocation while the grinder is operating on the work prior to and subsequent to the dressing operation to be different from the speed of reciprocation while the grinder is being dressed.

45. The combination with a grinding instrumentality, and means for causing a relative motion between it and the work, including means for causing a final cessation of said motion, and a dressing tool, of work engaging caliper mechanism, the position of which changes as the work is ground away, and mechanism operated by such change of position before and in advance of the said final cessation of the grinding motion for causing an engagement between said dressing tool and grinding instrumentality such as to dress the grinding surface of the latter and then to automatically restore the relative motion between said instrumentality and the work.

46. In a grinding machine, a reciprocating table, a wheel dressing device having its point normally out of the path of the grinding wheel, means operable by said table to move said dressing point into the path of the grinding wheel, and electromagnetic means for setting said means in operation.

47. In a grinding machine, a grinding wheel, a work caliper device, a wheel dressing device disposed normally out of the path of said grinding wheel, means set in operation by the movement of said work caliper device to a predetermined point for disposing said dressing device in the path of said wheel, and means for preventing a second disposal of said dressing device in said path during the subsequent grinding of the same piece of work.

48. In a grinding machine, a grinding wheel, a work caliper device, an electrical contact made by said device at an intermediate point in the grinding of each workpiece, for effecting the movement of said wheel through a wheel dressing position, and means, responsive to the return movement of said wheel, for preventing a second movement to wheel dressing position during the grinding of the same workpiece, notwithstanding the maintenance of said electrical contact.

In testimony whereof we have hereunto affixed our signatures.
